United States Patent Office

Des. 191,259
Patented Sept. 5, 1961

191,259

WHEEL COVER

George Albert Lyon, 13881 W. Chicago Blvd.,
Detroit, Mich.

Filed Jan. 4, 1960, Ser. No. 58,918

Term of patent 14 years

(Cl. D14—30)

FIGURE 1 is a front elevation of a wheel cover, embodying my new design;

FIGURE 2 is a perspective view thereof;

FIGURE 3 is an enlarged fragmentary elevational view thereof; and

FIGURE 4 is a diametrical sectional view taken on the lines 4-4 of FIGURE 1.

I claim:

The ornamental design for a wheel cover, substantially as shown.
